(57) CLAIM

The ornamental design for a removable tumbler wine stem, as shown and described.

DESCRIPTION

FIG. 1 is a top, front, left side perspective view of a removable tumbler wine stem showing my new design;
FIG. 2 is a bottom, front, left side perspective view thereof;
FIG. 3 is a right side elevational view thereof, the left side elevational view being a mirror image thereof;
FIG. 4 is a back elevational view thereof;
FIG. 5 is a front elevational view thereof;
FIG. 6 is a top plan view thereof;
FIG. 7 is a bottom plan view thereof; and,
FIG. 8 is a right side elevational view of a second embodiment of a removable tumbler wine stem shown broken away for indeterminate length, that being the only difference from the embodiment shown in FIGS. 1-7.
